UNITED STATES PATENT OFFICE.

WILLIAM J. FRISBIE, OF CHICAGO, ILLINOIS, ASSIGNOR TO JUSTRITE MANUFACTURING COMPANY, OF CHICAGO, ILLINOIS, A CORPORATION OF ILLINOIS.

ACETYLENE LAMP.

Application filed October 28, 1920. Serial No. 420,071.

To all whom it may concern:

Be it known that I, WILLIAM J. FRISBIE, a citizen of the United States, and a resident of Chicago, in the county of Cook, 5 State of Illinois, have invented certain new and useful Improvements in Acetylene Lamps, of which the following is a specification.

My invention relates to acetylene lamps, 10 particularly to miners' cap lamps which usually comprise a water container, a carbide cup, and water flow controlling mechanism, together with a burner tip and a gas tube leading from the tip to the carbide cup to 15 receive the generated gas. Such lamps also usually have a pad of straining and cleaning material held in position in front of the gas tube inlet so as to clean the gas and remove as much as possible the moisture there- 20 from before the gas flows to the tip. The main object of my invention is to provide improved means for holding the pad mate- 25 rial in proper operating position. A great many devices usually in the form of plates or shallow cups are employed which have frictional engagement with the water tube structure or the water valve controlling structure to be slid on such structure and frictionally held thereon to in turn securely 30 hold the straining material in position in front of the gas tube inlet. More in detail, my invention involves an improved pad holding member which will more efficiently 35 clamp its supporting structure and hold it self firmly in place thereon, but which at the same time can be readily removed for the purpose of applying a fresh pad or for shifting the old pad to bring a new section thereof into position in front of the gas 40 tube inlet.

On the accompanying drawing, my im- 45 proved pad holder is clearly shown. On the drawing—

Fig. 1 is a side elevational view of a min- 50 er's cap lamp with the pad material, its holder member, and some of the surround- ing lamp parts in vertical diametral sec- 55 tion,

Fig. 2 is an underside view of the water 60 container structure with the carbide cup re- 65 moved and showing the pad holder in place,

Fig. 3 is an enlarged top view of the pad 70 holder,

Fig. 4 is a sectional view on plane 75 4—4, Fig. 3,

Fig. 5 is a sectional view on plane 5—5, Fig. 3, and

Fig. 6 is a sectional view similar to that of Fig. 5 but showing a modified construc- 60

The lamp shown is of the well known miners' cap type, comprising the water container C, the carbide cup D, which has threaded engagement with the water container, the valve supporting tube E, the reflector F, and the gas tube G, leading from the tip H to the lower wall I of the water container so as to communicate with the gas space when the carbide cup is secured to the water container and the gas is being generated. The water controlling mechanism shown is like that disclosed in Patent No. 1,303,658, issued May 13th, 1919, to Augie L. Hansen, the water tube J extending through the supporting tube E and being rotatable by means of the lever K, the lower end of the water tube forming a valve for engaging with the top of the valve seat L formed at the lower end of the tube E, wa- 70 ter flowing through the opening M into the 75 water tube and the outflow of the water being controlled by the co-operation of the valve end of the tube with the valve seat.

N represents the filter material usually in the form of a felt pad or washer having 85 an opening at its center whereby it may be slipped up along the tube E into position in front of the inlet to the gas duct G. The filter material holder of my invention is clearly shown in Figs. 3 to 6. Its general 90 shape is that of a shallow cylindrical cup, the body 10 being circular and having the peripheral flange 11, the central section of the body being deflected upwardly to form the shallow dome or crown 12. The crown 95 part 12 has the radially extending tongues 13 and 14 which were formed by cutting the slots 15 and 16 parallel with the dia- 100 metral line and then cutting the metal be- thereto, the opposed sections being then gradually bent at their ends to form finger grips 17 and 18 and to leave the rectangular passageway 19. Extending across the 105 crown section 12 at the under side thereof are the spring rods 20 and 21, these rods being parallel and at right angles with the direction of extent of the tongues 13 and 14. At their opposite ends these rods ex- 110 tend respectively through holes 22, 23 and

24, 25 which holes are formed in the slanting side wall 26 of the crown section 12. When the rods are farthest apart, they abut against the outer edges of their respective 5 holes and when thus fully spaced apart the distance between them in the rectangular opening 19 is sufficiently less than the outer diameter of the supporting tube E that when the holder is slipped over the tube 10 with the tube extending through the opening 19 between the rods, the rods will be sprung apart and their spring action will exert frictional engagement on the tube to lock the holder in adjusted position. The 15 holder is slipped on with flange 11 extending upwardly as clearly shown in Fig. 1 so that the filter material N is received within the flange and is carried into abutting engagement with the lower wall I of the water container 20 so as to extend across the inlet of the gas tube G. Gas generated in the carbide cup D will find its way through the slots 15 and 16 and the holes 22, 23, 24 and 25 and through the space around the tube in 25 the opening 19, and before the gas can reach the tube G, it must pass through the filter material and be cleaned.

The rods may be separate or as clearly shown on the drawing, a piece of spring wire 30 may be bent into U-shape so that the rod sections are connected together by the yoke 27, the yoke being of a length preferably to keep the rod sections spread apart normally in engagement with the outer edges of their 35 respective openings in the crown section 12. The yoke will also tend to stiffen the rods and add to their frictional engagement with the tube E when the holder is applied thereto. The tongues 13 and 14 preferably extend a 40 sufficient distance inwardly to hold the summits of the concave inner sides of the finger grips 17 and 18 along side of the rods but not quite touching them when the holder is removed from the tube E. When the 45 holder is applied and the rods are spread apart, they will abut against the grip ends of the tongues and the tongues will lend their springiness to resisting spread of the rods, so that the rods will then be quite firmly 50 pressed against the tube E and the frictional engagement greatly increased. By inserting the thumb and forefinger in the concave sides of the grip sections 17 and 18 the holder can be firmly held and can be thus readily 55 slipped into place along the tube E or withdrawn therefrom.

Where the rods are cylindrical and of comparatively small diameter, their engagement with the cylindrical surface of larger 60 diameter of the tube E will cause concentration of the clamping force along a very small area and this accounts for the strong grip that my improved holder takes on the supporting tube, the holder when pushed 65 upwardly into place to position the filter

material then firmly retaining its set position. Instead of having the rods of circular cross section, they could be of polygonal cross section as for example, triangular as shown in Fig. 6. The comparatively sharp inner edges of the rod would then securely anchor the rods on the tube E in adjusted position. 70

I thus produce a very simple and efficient holder for the filter material of miners' 75 lamps. The cup structure of the holder can be stamped integral from sheet metal and the rod structures are also very readily formed. The flanging and crowning of the holder adds greatly to its strength. I do 80 not desire to be limited to the exact construction shown and described as changes might readily be made which would still come within the scope of the invention. 85

I claim as follows:

1. In a gas lamp, the combination with a gas chamber having a gas outlet, a support adjacent said outlet, and filtering material in front of said outlet, of a holder for said filtering material comprising a frame, resilient rods held on said frame and spaced apart, said rods receiving said supporting member between them and being spread apart thereby to exert clamping action on said supporting member and to thereby hold 90 said frame in supporting position with reference to said filtering material. 95

2. In a gas lamp, the combination with a gas chamber having a gas outlet, filtering material in front of said outlet, and a supporting member adjacent said outlet, of a holder for the filtering material comprising a frame having an opening for receiving said supporting member, rods held at one end on said frame and extending across said opening at opposite sides of said supporting member, said rods being of resilient material and being spread apart by said supporting member to thereby exert clamping action thereon whereby to support said frame in holding position with reference to the filtering material. 100

3. In a gas burning lamp, the combination with a gas chamber having a gas outlet, filtering material in front of said outlet, and a supporting member near said outlet, of a holder for the filtering material comprising a frame having an opening therethrough for receiving said supporting member, rods held at their ends on said frame and extending across said opening to receive said supporting member between them, said rods being of resilient material and being normally spaced to be spread apart by said supporting member when applied thereto to thereby clamp said supporting member and hold 115 said frame in holding position relative to said filtering material. 120

4. In a gas burning lamp, the combination with a gas chamber having a gas outlet, 130

filtering material adjacent said outlet, and a supporting member near said outlet, of a holder for the filtering material comprising a frame having an opening for receiving

5 said supporting member, rods held at their ends by said frame with their intermediate sections spaced apart and extending across said opening, said rods being normally spaced apart a distance less than the width
10 of the supporting member and being of resilient material, said frame being applied to said supporting member with said rods at opposite sides thereof whereby said rods will be spread apart and will exert clamping
15 action on the supporting member to thereby hold said frame in holding position relative to said filtering material.

5. A supporting member for the filter pad of a miner's acetylene lamp comprising a circular frame, said frame having holes near its periphery, rods extending at their ends through said holes, the material of said frame being cut away between said rods to provide a supporting member receiving
25 opening, said rods being adapted to be spread apart by a supporting member inserted through said opening, said rods being springy whereby to exert clamping action on the supporting member when spread apart
30 thereby.

6. A holder for the filtering pad in a miner's acetylene lamp comprising a circular metallic frame having its central section crowned, there being holes through said frame at the base of the crowned section, rods on the under side of said crown section extending at their ends through said holes to be thereby anchored on said frame, the frame material being cut away between
35 said rods to provide an opening for receiving a supporting member, said rods when spread apart by a supporting member being adapted to exert clamping action thereon to hold the holder in place.

45 7. A holder for the filter pad in a miner's acetylene lamp comprising a circular frame having an upstanding peripheral flange and having its central section crowned upwardly, holes through said frame at the base of said crowned section, rods at the under side of said crowned section extending at their ends through said holes to the opposite side of the crowned section, the material of said frame being cut away between said rods to
50 leave a central opening for the reception of a supporting member, said rods when spread

apart by a supporting member being adapted to exert clamping action on such member to thereby hold the holder in place
55 on such member.

60

8. The combination with a gas chamber having a gas outlet, filtering material in front of said outlet, and a supporting member near said outlet, of a holder for said filtering material comprising a sheet metal frame having tongues cut therefrom and extending radially inwardly and deflected downwardly at their ends to leave an opening through said frame for receiving said supporting member, resilient rods held at
65 their ends on said frame and extending across said opening alongside the inner side of said tongues to receive said supporting member between them, said rods being spread apart by said supporting member to
70 thereby exert clamping action thereon to hold said frame in holding position relative to the filtering material, said tongues being positioned to be eventually engaged by said rods to assist said rods in clamping said
75 supporting member, the tongue ends serving as finger grips for applying or removing said frame from said supporting member.

9. The combination with a gas generator having a gas outlet, filtering material in front of said outlet, and a supporting member near said outlet, of a holder for said filtering material comprising a circular plate, said plate having a central opening for receiving said supporting member, rods of resilient material spaced apart and extending across said opening, said rods being held by said frame at their ends against spreading apart but being free to be spread apart where they cross said opening, said rods receiving said supporting member between them when said frame is applied to said member and being spread apart to thereby exert clamping action on said supporting member to hold said frame in holding position relative to the filtering material, and tongues deflected from the material of said frame and extending alongside of said rods at said opening in position to be engaged by said rods after preliminary spreading apart
90 of said rods to resist further spread apart of said rods and assist them in clamping
95 said supporting member.

In witness whereof, I hereunto subscribe my name this 22nd day of October, A. D., 110
1920.

WILLIAM J. FRISBIE.
